UNITED STATES PATENT OFFICE.

CLARENCE W. COLEMAN, OF WESTFIELD, NEW JERSEY, ASSIGNEE TO THE HALL SIGNAL COMPANY, A CORPORATION OF MAINE.

RAILWAY-SEMAPHORE.

No. 882,920.

Specification of Letters Patent. Patented March 24, 1908.

Application filed October 31, 1905, Serial No. 285,272. Renewed October 12, 1907. Serial No. 397,169.

To all whom it may concern:

Be it known that I, CLARENCE W. COLEMAN, a citizen of the United States, residing at Westfield, in the county of Union and State of New Jersey, have invented certain new and useful Improvements in Railway-Semaphores, of which the following is a specification, reference being had therein to the accompanying drawing, forming a part thereof.

My invention relates to semaphores such as disclosed in the Loree and Patenall Patent No. 733,981, July 21, 1903, wherein the semaphore-blade moves through the upper quadrant and the weight of snow and ice upon the semaphore-blade, instead of being an element of danger, is an element of safety, increasing the normal tendency of the semaphore to the danger position.

My invention has for its principal object to provide a semaphore having one or more spectacle-openings on one side of its pivot and weighted on the other side of its pivot independently of the blade so as to go to danger by gravity whether assisted by the blade or further assisted by snow and ice on the blade or deprived of the assistance of the blade by reason of the fact that the blade has been broken off or disconnected; so that the spectacle portion would go to danger at all times and under all conditions except when forcibly moved to clear by the operating mechanism.

Other objects of my invention will appear from the following description of the apparatus embodying my invention which is illustrated in the accompanying drawings.

I will now describe such apparatus and will thereafter point out my invention in claims.

Figure 1 is a front elevation of a semaphore and the upper part of its supporting post, with the semaphore in the danger position. Fig. 2 is a plan view of the same with the post in section. Figs. 3 and 4 are front elevations of the parts shown in Fig. 1, with the semaphore in the two other positions of indication, Fig. 3 showing the caution or distant danger position and Fig. 4 the safety or clear position. Fig. 5 is a front elevation of a semaphore and the upper part of its supporting post, this semaphore being of modified construction to adapt it for co-operation with a signal-lamp held on top of

the post and being shown in the safety position. Fig. 6 is an end elevation of the same. Fig. 7 is a front elevation of the same, with the semaphore in the danger position.

I will first describe the construction shown in Figs. 1 to 4, inclusive. Here the semaphore-post *a* is of standard construction, as is also the signal-lamp *b*, and the signal-lamp is, as usual in double track block-signals, supported on a bracket *c* at the side of the post opposite to that at which the semaphore-blade *d* is located. The semaphore comprises the blade *d* and the spectacle portion *e*, these two portions of the semaphore being made in two parts, the spectacle portion, or, as it is usually termed, the spectacle-casting, including the pivot and spectacle-openings and carrying the semaphore-blade, the semaphore-blade being bolted to the spectacle portion in the usual manner. Three spectacle-openings, *g*, *y* and *r*, are formed in the spectacle portion and are located so as to co-operate with the signal-lamp in the different positions of the semaphore. Spectacles or colored or colorless glasses may be fitted in these spectacle-openings in any desired manner, or the spectacle-openings may be partly unprovided with spectacles, as may be desired, to adapt the semaphore for use as a three-position signal, a two-position home-signal, a two-position distant-signal, a switch-signal, or to any of the uses of a railway-signal. As shown, a spectacle is provided in each opening, which may be green at *g* for safety, yellow at *y* for caution and red at *r* for danger.

By reason of the fact that the signal-lamp is located at the side of the post opposite to that at which the semaphore-blade projects, the part of the spectacle-portion which has the spectacle-openings therein is largely located at the lamp side of the post. If the semaphore-blade is made of wood, its weight will not be great, but will be added to that of the part of the spectacle portion at the blade side of the pivot, and it will moreover provide a large surface upon which snow and ice may accumulate, and the weight of snow and ice on the blade will only increase the normal tendency of the semaphore to danger position. It is to be noted that the part of the spectacle portion which is on the side of the pivot opposite the blade side does not

have a large surface and is comparatively near the center and could not therefore, with a maximum accumulation of snow and ice thereon, exert a countervailing force such as could materially disturb the normal tendency to danger, while the blade, extending out as it does a very considerable distance from the center and having a large surface, may not only accumulate a considerable quantity of snow and ice but would carry such an accumulation at comparatively large distances from the center, with consequent considerable leverage, so that accumulations of snow and ice on the blade, which 15 would always add to the normal tendency to danger position, may at times exert a considerable gravitational force. In view of the fact, however, that the blade is connected to the spectacle portion by fastening devices, 20 which may possibly become loosened, and that it may be broken off or torn off by extraordinary wind pressure or otherwise, and that at night such a broken condition would not be evident, I provide against any possibility of the absence of the weight of the 25 semaphore-blade by separately weighting the spectacle portion on the blade side so that it will go to danger independently of the blade. Therefore, whether or not the blade is secured to the spectacle portion, the spectacle portion will gravitate to danger position at all times except when compelled by the mechanism to give safety indications. This weighting I effect by thickening the part e' 30 of the spectacle portion in proximity to the point of fastening of the blade, such part of the spectacle portion being the part thereof at greatest distance from the pivotal center on the blade side of the pivot, and being located at the blade side of the pivot in all positions of the semaphore.

The semaphore is secured to the semaphore-shaft j , on which is also secured a crank k ; and an operating wire l is secured to 45 the crank and operates to pull the signal to clear under the control of automatic or manually operated mechanism as may be desired, with lever, gas, pneumatic, electrical or other operating mechanism.

50 The upper vertical or clear position of the semaphore is shown in Fig. 4. From this position it gravitates to the horizontal or danger position and its movement is arrested at this position by a stop-screw q on the signal-post, engaging the crank k on the semaphore-shaft. A jam-nut q' locks the stop-screw in proper position.

The construction shown in Figs. 5, 6 and 7 differs from that shown in Figs. 1 to 4, inclusive, in that the spectacle-openings are located so as to coöperate with a signal-lamp b' on top of the semaphore-post, as is desirable where semaphores for two directions are mounted upon the same post. Here the spectacle portion is largely above the pivot

when the semaphore is in the safety position. The construction here shown embodies the present invention in that the spectacle portion is weighted on the blade side so as to go to danger independently of the blade. The thickened or weighted part e' is located at the lower right hand corner of the spectacle portion. The post a' has its upper portion removed to provide for the proper placing and support of the lamp. In other respects the construction is the same as that above described. The actuating mechanisms for the semaphores are not shown, as any ordinary or suitable actuating mechanism may be employed.

It is obvious that various modifications may be made in the constructions shown and above particularly described within the principle and scope of my invention.

What I claim and desire to secure by Letters Patent is:—

1. The combination, with a semaphore-support, of a pivotally mounted semaphore including a spectacle portion and a semaphore-blade, the semaphore-blade being movable with the spectacle portion and movable downward from the safety to the danger position, the semaphore having a spectacle-opening on one side of its pivot and being weighted on the other side of its pivot so as to go to danger by gravity independently of the blade.

2. The combination, with a semaphore-support, of a pivotally mounted semaphore including a spectacle portion and a semaphore-blade, the spectacle portion and semaphore-blade being in separate pieces connected so as to move together and the blade being movable downward from the safety to the danger position, the semaphore having a spectacle-opening on one side of its pivot and being weighted on the other side of its pivot so as to go to danger by gravity independently of the blade.

3. The combination, with a semaphore-support, of a pivotally mounted semaphore including a spectacle portion and a semaphore-blade, the spectacle portion and semaphore-blade being in separate pieces connected so as to move together about a common pivotal center, the semaphore-blade being located at one side of the pivotal center and arranged so as to move downward from the safety to the danger position and the semaphore having a spectacle-opening located at the side of the pivotal center opposite that at which the blade is located and being weighted on the blade side of the pivotal center so as to go to danger by gravity independently of the blade.

4. The combination, with a semaphore-support, of a semaphore including a pivotally mounted spectacle portion and a semaphore-blade, the spectacle portion and semaphore-blade being in separate pieces con-

ected so as to move together and the blade being movable downward from the safety to the danger position, the spectacle portion having a spectacle-opening on one side 5 of its pivot and being separately weighted on the other side of its pivot so as to go to danger by gravity independently of the blade.

5. The combination, with a semaphore-support, of a semaphore including a pivotally mounted spectacle portion and semaphore-blade, the spectacle portion and semaphore-blade being in separate pieces connected so as to move together about a common pivotal center, the semaphore-blade 10 being located at one side of the pivotal center and arranged so as to move downward from the safety to the danger position, and the spectacle portion having a spectacle-opening located at the side of the pivotal center opposite that at which the blade is located and being separately weighted on the blade side of the pivotal center so as to go to danger by gravity independently of the blade.

6. The combination, with a semaphore-support, of a semaphore including a spectacle portion and semaphore-blade, the semaphore being pivotally mounted on a center at one side of the blade so that the blade is at one 15 side of the pivotal center and the spectacle portion has a spectacle-opening at the other side of the pivotal center when the semaphore is in the safety position and being arranged so that the blade moves downward 20 from the safety to the danger position, the semaphore being weighted on the blade side of the pivotal center so as to go to danger by gravity independently of the blade.

7. The combination, with a semaphore-support, of a semaphore including a spectacle portion and semaphore-blade, the semaphore being pivotally mounted on a center at one side of the blade and arranged relatively to its pivotal center so that the blade is at one side of the pivotal center and the spectacle portion is at both sides of the pivotal center when the semaphore is in the safety position and so that the blade moves downward from the safety to the danger 25 position, the spectacle portion being separately weighted on the blade side of the pivotal center so as to go to danger by gravity independently of the blade.

8. The combination, with a semaphore-support, of a semaphore including a spectacle portion and semaphore-blade, the spectacle portion and semaphore-blade being in separate pieces connected so as to move together about a common pivotal center 30 located at one side of the blade and the semaphore being arranged relatively to the pivotal center so that the blade is at one side of the pivotal center and the spectacle portion is at both sides of the pivotal center 35 when the semaphore is in the safety position

and so that the blade moves downward from the safety to the danger position, the spectacle portion being separately weighted on the blade side of the pivotal center so as to go to danger by gravity independently of the blade.

9. The combination, with a semaphore-support, of a semaphore including a spectacle portion and semaphore-blade, the semaphore being pivotally mounted on a center at one side of the blade and supported so that the blade is located at one side of the support, and a signal-lamp located at the other side of the support, the spectacle portion having a spectacle-opening disposed so as to coöperate with the lamp, the semaphore being weighted on the blade side of the pivotal center so as to go to danger by gravity independently of the blade, and the blade being moved downward from the safety to the danger position.

10. The combination, with a semaphore-support, of a semaphore including a spectacle portion and semaphore-blade, the semaphore being pivotally mounted on a center at one side of the blade and supported so that the blade is located at one side of the support, and a signal-lamp located at the other side of the support, the spectacle portion having a spectacle-opening disposed so as to coöperate with the lamp and being separately weighted on the blade side of the pivotal center so as to go to danger by gravity independently of the blade, and the blade being movable downward from the safety to the danger position.

11. The combination, with a semaphore-support, of a semaphore including a spectacle portion and a semaphore-blade, the spectacle portion and semaphore-blade being in separate pieces connected so as to move together about a common pivotal center located at one side of the blade, and the semaphore being supported so that the blade is located at one side of the support, and a signal-lamp located at the other side of the support, the spectacle portion having a spectacle-opening disposed so as to coöperate with the lamp, the semaphore being weighted on the blade side of the pivotal center so as to go to danger by gravity independently of the blade, and the blade being movable downward from the safety to the danger position.

12. The combination, with a semaphore-support, of a semaphore including a spectacle portion and semaphore-blade, the spectacle portion and semaphore-blade being in separate pieces connected so as to move together about a common pivotal center located at one side of the blade, and the semaphore being supported so that the blade is located at one side of the support, and a signal-lamp located at the other side of the support, the spectacle portion having a

spectacle-opening disposed so as to coöperate with the lamp and being separately weighted on the blade side of the pivotal center so as to go to danger by gravity independently of the blade, and the blade being movable downward from the safety to the danger position.

In testimony whereof I have affixed my signature in presence of two witnesses.

CLARENCE W. COLEMAN.
